UNITED STATES PATENT OFFICE.

WILLIAM MILO LEWIS, OF NEW HARTFORD, IOWA.

METAL FENCE-POST.

1,075,984.

Specification of Letters Patent.

Patented Oct. 14, 1913.

Application filed January 16, 1913. Serial No. 742,436.

To all whom it may concern:

Be it known that I, WILLIAM MILO LEWIS, a citizen of the United States, residing at New Hartford, in the county of Butler and 5 State of Iowa, have invented certain new and useful Improvements in Metal Fence-Posts; and I do declare the following to be a full, clear, and exact description of the invention, such as will enable others skilled 10 in the art to which it appertains to make and use the same.

This invention relates to improvements in metal fence posts.

One object of the invention is to provide 15 a fence post of this character having an improved means for securely fastening a fence wire thereto whereby the wire is locked and held against longitudinal movement.

Another object is to provide means where- 20 by the wire fastening devices after locking the wire are securely fastened against disengagement or removal from the fence post.

With these and other objects in view, the 25 invention consists of certain novel features of construction and the combination and arrangement of parts as will be more fully described and claimed.

In the accompanying drawings: Figure 1 is an outer side view of a fence post con- 30 structed in accordance with my invention and showing the line wires of the fence applied thereto; Fig. 2 is an inner side view of the same; Fig. 3 is a horizontal sectional view taken on the line 3—3 of Fig. 2; Fig. 35 4 is a similar view taken on the line 4—4 of Fig. 2; Fig. 5 is a central vertical sectional view of the post; Fig. 6 is a detail perspective view of a portion of one of my im- proved posts.

40 My improved fence post comprises a body portion 1 in the form of an angle iron bar which may be of any suitable size and any desired length and which when set up for use has its lower end embedded in or se- 45 cured to a concrete or any other form of base or anchoring device (not shown).

At intervals or at suitable distances apart in the corner or apex of the post are formed transverse or horizontally disposed wire re- 50 ceiving slots 2 with which the line wires of the fence are adapted to be engaged. Above each of the slots 2 the apex or angular corner of the post is swaged or forced out- 55 wardly as at 3 to form in the inner side of the angle of the post a rearwardly inclined guide groove 4 to receive the fastening de-

vices 5 for the fence wire hereinafter de- 60 scribed. Below each of the slots 2 the apex or angle of the post is swaged or pressed outwardly as at 6 to form in the inner side 65 or angle of the post an inclined clenching groove 7 for the lower end of the wire fas- tening device whereby said end is turned inwardly after being driven behind the fence wire or between the fence wire and the groove 3 in the inner side of the post as will be hereinafter more fully described. It will be noted that the swaged portions 6 of the post are forced back to a greater extent than the swaged portions 3 above the slots 70 and that the clenching groove 7 in said swaged portions 6 has its upper end extending out farther than or terminating in a plane beyond the plane in which the lower end of the groove 4 terminates, thus insur- 75 ing the proper engagement of the end of the wire fastening device with said groove 7 for the purpose of upsetting or turning the end of the fastening device.

The wire fastening devices 5 are in the 80 form of tapered pins of suitable size and length and are formed of malleable metal or are capable of being bent and clenched into engagement with the post for holding 85 the line wires 8 of the fence in locked en- gagement with the slots 2 of the post. In fastening the line wires 8 to the post said wires are inserted in the slots 2 and are brought into engagement with the inner 90 ends thereof after which the pointed or ta- pered ends of the pins 5 are engaged with the grooves 4 in the offset portions 3 of the post and are forced behind the wires 8 or between the same and the inner walls of the 95 grooves 4 until the points of the pins come into engagement with the upper ends of the grooves 7 in the offset portions 6 as clearly indicated in dotted lines in Fig. 5 of the drawings. After the fastening pins have thus been engaged with the post, the pins 100 are driven downwardly whereupon the inclined surface of the grooves 7 will turn the ends 9 of the pins inwardly below the wires 8. After the pins have been driven down- 105 wardly and the lower ends thereof turned inwardly a sufficient distance to project the points of the pins beyond the lower end of the grooves 7 and a suitable distance be- 110 yond the inner side of the apex of the post the points or lower ends of the pins are up- set or turned back into engagement with the inner side or apex of the post, thus effectu-

ally locking the pins and preventing the same from being pulled upwardly or removed until the upset lower ends 9 have been straightened. When the pins are driven downwardly in the grooves 4 of the post and forced between the lower ends of the grooves 3 and the outer sides of the line wires 8 of the fence the increasing size of the pins due to the tapered structure thereof will bend said line wires inwardly or form kinks or short curves 10 in said wires 8 as clearly shown in Fig. 4 of the drawings. The kinks 10 when thus formed provide an interlocking engagement with the pins and also form projections on the inner sides of the wires both of which conditions will lock the line wires of the fence against longitudinal movement in the slots 2 of the fence post, thus not only securely fastening the wires to the post, but also causing the successive posts of the fence to brace each other through the line wires of the fence as will be readily understood.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described my invention, what I claim is:

1. A fence post comprising a body portion having therein transverse wire receiving slots which are cut through from the outer to the inner side of the post, said post having in its inner side above said transverse slots an outwardly and downwardly inclined guide groove and below said slots an outwardly and upwardly inclined clenching groove, the upper end of which terminates beyond the lower end of the guide groove above the slot, and tapered wire fastening pins adapted to be engaged with said guide grooves and between the in-

ner surface thereof and the outer side of the fence wire and to be driven downwardly between the wire and the wall of the groove whereby the lower end of the pin is forcibly engaged with said clenching groove and thereby turned inwardly until the point of the pin projects beyond the lower end of the clenching groove, said point being upset into clenching engagement with the inner side of the post.

2. A fence post comprising an angle iron body having in the apex or angular corner thereof a series of transversely disposed wire receiving slots which are cut through to the inner side of the post, said post having its apex swaged outwardly above said slots to form downwardly and outwardly inclined guide grooves and having its apex below said grooves swaged outwardly to form upwardly and outwardly inclined clenching grooves, said guiding and clenching grooves communicating with said slots, tapered wire fastening pins adapted to be engaged with said wire guiding grooves between the wires of the fence and the inner walls of the groove whereby when the pins are driven downwardly the lower ends thereof will be engaged with said inclined clenching groove and will be thereby turned inwardly until the point of the pin projects beyond the lower end of the groove, said pointed end of the pins being upset and clenched into engagement with the inner side of the post, the tapered structure of said pins when thus driven through the guide grooves 4 and into engagement with the clenching grooves bending or kinking the wires of the fence whereby the latter are locked against longitudinal movement in the wire receiving slots of the post.

In testimony whereof I have hereunto set my hand in presence of two subscribing witnesses.

WILLIAM MILO LEWIS.
